UNITED STATES PATENT OFFICE.

EDWARD KNOX, OF MONTREAL, QUEBEC, CANADA.

POLISH FOR FURNITURE.

1,088,998.

Specification of Letters Patent.

Patented Mar. 3, 1914.

No Drawing.

Application filed March 17, 1913. Serial No. 754,861.

To all whom it may concern:

Be it known that I, EDWARD KNOX, a subject of the King of Great Britain, and resident of the city and district of Montreal, in 5 the Province of Quebec, in the Dominion of Canada, have invented certain new and useful Improvements in Polishes for Furniture; and I do hereby declare that the following is a full, clear, and exact description 10 of the same.

The invention relates to improvements in a new and useful composition of matter used for the purpose of polishing furniture and the like and the object of the invention is to 15 provide a mixture of ingredients, which will not in any way damage the furniture and at the same time give the said furniture a brilliant finish and it consists essentially of the novel combination of ingredients not used 20 together previously for the aforesaid purpose as more particularly set forth in detail hereinafter and pointed out in the claims.

The composition is made up of about two 25 quarts of raw linseed oil, two pints of vinegar, one pint of highwines, six eggs and one

half pound of sugar. These ingredients are taken and thoroughly mixed together preferably by agitation.

In use the mixture is applied on the furniture with a soft cloth and rubbed dry with 30 another soft cloth completing the finished surface.

What I claim is:—

1. The herein described composition of matter consisting of raw linseed oil, vinegar, high wines, eggs and sugar, substantially and for the purpose specified. 35

2. The herein described composition of matter for polishing furniture, consisting of raw linseed oil two quarts, vinegar two 40 pints, high wines one pint, eggs six, and sugar one half pound substantially as described.

Signed at the city of Montreal, Quebec, Canada, this 12th day of February, 1913. 45

EDWARD KNOX.
